COPY PRINTING MECHANISM

Harry D. Atwood, Detroit, Mich., assignor of
one-half to J. C. Trimby, Detroit, Mich.

Application September 3, 1932, Serial No. 631,641

8 Claims. (Cl. 197—153)

This invention relates to copy-printing attachments for typewriters and similar machines and more particularly to the printing of copies by an auxiliary inking ribbon lying alongside the main printing ribbon.

The general object of the present invention is to provide a new and improved copy-printing attachment of the above character which is simple and inexpensive in construction, convenient and reliable in operation, and readily adaptable to standard typewriter constructions.

Another object is to provide a novel mechanism for supporting the copy-printing ribbon and maintaining the same in proper relation to the main ribbon while at the same time permitting movement thereof into and out of active position.

A further object is to provide a novel means for effecting feed of the copy-printing ribbon automatically and also reversal of such feed.

The invention also resides in the novel and compact arrangement of the parts permitting the use of a second copy ribbon for printing fourth and fifth copies.

Other objects and advantages of the invention will become apparent from the following detailed description taken in connection with the accompanying drawings in which

Figure 1 is a perspective view of a copy-printing attachment embodying the features of the present invention.

Fig. 2 is an end elevational view.

Fig. 3 is a section taken along the line 3—3 of Fig. 2.

Fig. 4 is a section taken along the line 4—4 of Fig. 3.

Fig. 5 is a perspective view of the parts of the mechanism for effecting reversal of the ribbon feed.

Fig. 6 is a fragmentary perspective view of the line-spacing lever of a typewriter and the parts of the copy-printing attachment actuated thereby.

In the exemplary form shown in the drawings, the numeral 7 represents the side frames of the carriage frame on a standard typewriter having a rotatably supported platen 8 opposite which the main ribbon 9 is led through guides 10. Step-by-step rotation of the platen to effect line-spacing and lateral shifting of the carriage are effected by well known ratchet mechanism (not shown) actuated by the usual hand lever 11 pivoted at 12 on the carriage.

The auxiliary ribbon by which second and third copies may be printed comprises an inked strip

13 having opposite ends wound on spools 14 and the intermediate portion led through inclined slots 15 in depending arms 16 and thus adapted for movement in a vertical plane into and out of printing position behind the main ribbon 9. At their upper ends, the arms 16 are attached to blocks 22, bolted to intermediate blocks 17 providing journals for opposite ends of a tubular shaft 18 upon which the spools 14 are loosely mounted between the blocks. The latter are disposed in vertical guide slots 19 in parallel plates 20 having flanges 21 at their lower ends bolted or otherwise suitably secured to the carriage frame plates 7 and connected at their rear ends by a bar 21a along the upper sides thereof. Plates 22 secured to the blocks 17 on opposite sides of the plates 20 serve to maintain the ribbon-supporting arms 16 in properly spaced relation.

Extending through the tube 18 with ends projecting beyond the ends of the latter is a shaft 23 having pinions 24 fast on its opposite ends and meshing with the teeth of two vertical bars 25 secured at their lower ends to the flanges 21 and at their upper ends to the plates 20. The shaft 23 thus supports the spools 14 and by virtue of the constant engagement of the pinions 24 with the stationary rack bars, the shaft is always maintained in exactly horizontal position while at the same time being adapted for bodily movement in a vertical plane to carry the ribbon 13 into and out of the active position shown in Fig. 3.

Automatic advance of the ribbon 13 as an incident to normal operation of the typewriter is effected through the medium of a slide bar 26 supported on the left hand flange 21 and between the plate 20 and the rack bar 25 and having a lateral arm 27 (Fig. 6) rigid therewith and depending therefrom into a position to be engaged by the usual arm 28 on the line-space lever 11. Pivoted on the slide and normally urged upwardly by a spring 29 into a position determined by a stop pin 30 is a pawl 31 adapted, when the ribbon 13 is lowered to active position, to be brought into engagement with teeth 32 on the periphery of a ratchet wheel 33 fast upon the end of the tubular shaft 18. As the slide 26 is moved rearwardly upon actuation of the line-space lever 11, the pawl 31 catches behind one of the teeth 32 and advances the shaft 18. Upon release of the lever 11 a spring 34 acting on the usual line-spacing slide 34' returns the slide 26 to its initial position. Thus in normal operation of the typewriter with the ribbon 13 lowered to active position, a step-by-step movement will be imparted to the shaft. When the

ribbon and its supporting parts are raised to inactive position as shown in Fig. 1, the ratchet wheel is withdrawn from operative association with the pawl so that the shaft 18 will not be advanced in the subsequent operation of the typewriter.

Means is provided for coupling one or the other of the spools 14 to the shaft 18 and thereby cause the ribbon 13 to be advanced in one direction or the other. In the present instance, this means comprises a pair of clutches 35 and 36 having a single control element in the form of a tube 37 enclosing the shaft 18 and adapted to be shifted axially between two positions in either of which the tube is maintained by a spring detent 38 housed within a knurled sleeve 39 by which the tube is grasped during shifting. Each of the clutches comprises a hub 40 fast on the end of the tube 37 and having teeth 41 projecting axially beyond lugs 42 on the shaft 18 and having inner ends adapted to enter apertures 43 in the hub portion of the adjacent spool. When the tube 37 is shifted to the right as shown in Fig. 3, the clutch 36 will be engaged and the clutch 35 disengaged with the result that rotation of the shaft 18 will advance the ribbon 13 to the right unwinding the same from the left-hand spool and winding the ribbon onto the right-hand spool. Upon shifting the tube 37 into its other position, the clutch 35 will be engaged thereby adapting the feed mechanism for advance of the ribbon 13 in the reverse direction. In the event that the teeth 41 do not enter the holes 43 properly upon shifting of the tube 37, such entry will be permitted upon twisting the tube slightly as permitted by the relatively wide spacing of the teeth 41.

To avoid slackness in the ribbon by overrunning of the spool from which the ribbon is being unwound, provision is made for the application of frictional forces constantly resisting rotation of the spools 14. For this purpose, friction brakes may be employed each comprising a drum 44 fast on the shaft 18 adjacent each spool and a resilient band 45 encircling the drum with its opposite ends anchored to a pin 46 on the spool. The degree of braking action may be adjusted by the screw 47.

The spool from which the ribbon is unwound in the active motion of the slide 26 will tend to turn backwardly upon retraction of the slide which turning would, if permitted, produce considerable slack in the ribbon permitting the ribbon to move laterally relative to the paper causing smearing thereof. To avoid this, a pawl 48 (Fig. 2) is pivoted at 49 on the plate 22 and urged toward the teeth 32 by a spring 51 and the teeth 32 are spaced so close together that the pawl will be disposed close to one of the shoulders on the teeth so as to prevent any substantial reverse movement of the ratchet wheel as the movement of the slide 26 reverses.

The copy-printing attachment above described is adapted for printing two copies of the original, one on a paper sheet placed behind the ribbon 13 and the other on a transparent sheet disposed between the ribbons 9 and 13. To provide for printing two additional copies, a second auxiliary ribbon 52 may be employed with its opposite ends wound on spools 53 and its intermediate portion extending around rollers 54 and through guide slots 55 in depending arms 56. The latter and the spools 53 are mounted for vertical movement on the plates 20 in the same manner as the arms and

spools for the ribbon 13. The spools are maintained in horizontal position in the same way as the first mentioned spools, the rack-bars 57 engaging the pinions on the spool supporting shaft having teeth facing in the opposite direction from the teeth on the bars 25. This enables the spools 14 and 53 to be placed close together thereby contributing to the overall compactness of the attachment as a whole.

When it is desired to use the ribbon 52, the supporting means therefor is lowered by grasping the sleeve 58 thereby bringing the intermediate portion of the ribbon alongside the ribbon 13 as shown in Fig. 2. In such movement a ratchet wheel 59 for advancing the ribbon 52 is brought into engagement with a pawl 60 so that the ribbon will be advanced in the same manner as the ribbon 13. If only three copies are to be printed, the ribbon 52 is raised to inactive position as shown in Fig. 1.

From the foregoing it will be apparent that the attachment provided is readily adaptable to standard typewriter constructions and is rendered exceedingly compact and simple in construction by virtue of the novel manner of guiding the ribbon spool supporting means and the relation of the guides for the different ribbons. In addition, manipulation of the attachment for reversing the direction of ribbon feed is rendered simple and convenient by employing a single clutch control element.

I claim as my invention:

1. In combination with a typewriter having a laterally shiftable carriage frame with a platen roller thereon, two upright members secured to opposite ends of said frame and each having oppositely facing rack-teeth along their forward and rearward vertical edges, two parallel horizontal shafts adapted for independent vertical movement and having pinions on their opposite ends meshing with said racks whereby to maintain the shafts in horizontal positions, a pair of spools on each of said shafts, two copy ribbons each having opposite ends wound on the spools on one of said shafts and a substantially straight intermediate portion movable vertically with the shaft, and means for turning said shafts automatically as an incident to normal operation of said typewriter with the shafts lowered to bring the ribbons opposite said platen roller.

2. In combination with a typewriter having a laterally shiftable carriage frame with a platen roller thereon, two upright members secured to opposite ends of said frame, a pair of parallel horizontal shafts guided for bodily vertical movement by said members, a pair of spools on opposite ends of each shaft, a pair of copy-printing ribbons each having opposite ends wound on the spools of one pair, ratchet wheels each on the end of one of said shafts, a horizontal slide adapted to be shifted rearwardly by operation of the line-spacing lever of said typewriter, and a pair of pawls mounted on said slide and adapted to engage the respective ratchet wheels upon lowering of said shafts.

3. In a typewriting machine, means for supporting a copy-printing ribbon for vertical movement into and out of active position comprising a horizontal tubular shaft, a pair of spools loosely mounted on opposite ends of said shaft and having opposite ends of said ribbon wound thereon, means by which one or the other of said spools may be coupled to said shaft, a pair of stationary upright rack-bars at opposite ends of said shaft, and a shaft extending through said tubular shaft

- and having pinions fast on its opposite ends and meshing with said rack-bars whereby to maintain said tubular shaft in horizontal position during vertical movement thereof.
5. 4. In a typewriting machine, means for supporting a copy-printing ribbon for vertical movement into and out of active position comprising a pair of concentric shafts one rotatable within the other, a pair of spools loose on opposite ends 5 of one of said shafts and having opposite ends of said ribbon wound thereon, means by which one or the other of said spools may be coupled to the latter shaft, means for turning the latter to advance the intermediate portion of the ribbon longitudinally of the shaft, a pair of stationary upright rack-bars, and pinions on opposite ends of said other shaft meshing with the respective rack-bars.
5. In a typewriting machine, means for supporting a copy-printing ribbon for vertical movement into and out of active position comprising a pair of horizontal concentric shafts guided for bodily vertical movement, a pair of spools on opposite ends of one of said shafts having opposite 25 ends of said ribbon wound thereon and adapted to be coupled selectively to the latter shaft, and means operatively associated with opposite ends of the other shaft to maintain the shafts in horizontal position during vertical movement thereof.
30. 6. In combination with a typewriter, a horizontal shaft mounted on the typewriter carriage for vertical movement, a pair of spools loose on opposite ends of said shaft, a copy-ribbon having opposite ends wound on said spools, a frame movable with said shaft and providing guides leading the intermediate portion of the ribbon in a straight path parallel to the typewriter platen, means by which one of said spools may be coupled to said shaft while the other is uncoupled 35 therefrom, means resisting overrunning of the uncoupled spool, a pawl and ratchet mechanism actuated by the line-spacing lever of the type-
- writer to advance said shaft with a step-by-step motion, and retaining means engaging the ratchet mechanism to limit reverse movement of the shaft after release of the line-space lever, said retaining means and the teeth of the ratchet being arranged to become effective immediately upon retraction of said lever whereby to prevent the occurrence of slack in the straight portion of said ribbon.
7. In combination with a typewriter having a line-space member arranged for manual oscillation, a horizontal shaft mounted on the typewriter carriage for bodily vertical movement, a pair of spools loose on opposite ends of said shaft, a copy-printing ribbon having opposite ends wound on said spools and its intermediate portion guided in a straight path parallel to the typewriter platen, means by which one of said spools may be coupled to said shaft while the other is uncoupled therefrom, means providing a one-way driving connection between the line-space member and said shaft whereby to advance the shaft upon movement of the member in one direction, and means becoming operative immediately upon the initial retracting movement of said member to hold said shaft against reverse movement whereby to maintain the straight portion of said ribbon taut.
8. In a typewriting machine, means for supporting a copy printing ribbon for vertical movement into and out of active position comprising a pair of horizontal shafts mounted to turn about a common axis and arranged for bodily vertical movement, a pair of spools at opposite ends of one of said shafts having opposite ends of said ribbon wound thereon and adapted to be driven by the latter shaft, and means operatively associated with opposite ends of the other shafts to maintain the shafts in horizontal position during vertical movement thereof to carry said ribbon 40 into and out of printing position.

HARRY D. ATWOOD.
